UNITED STATES PATENT OFFICE.

ARCHIBALD F. REDDIE, OF PHILADELPHIA, PENNSYLVANIA, ASSIGNOR TO McCALLUM & McCALLUM, OF SAME PLACE.

DESIGN FOR CARPET.

SPECIFICATION forming part of Design No. 24,054, dated February 19, 1895.

Application filed January 26, 1895. Serial No. 536,380. Term of patent 3½ years.

To all whom it may concern:

Be it known that I, ARCHIBALD F. REDDIE, a citizen of the United States, residing at Philadelphia, county of Philadelphia, and 5 State of Pennsylvania, have invented and produced a new and original Design for a Carpet or other Fabric, of which the following is a specification and description.

The design of my invention may be applied 10 to or wrought in Brussels, Wilton or other carpetings in such colors and combinations of colors as may be desired; and I do hereby declare that the drawing accompanying this specification presents to the eye of the ob- 15 server a clear understanding of my new and original design sufficient to enable such person to ascertain its leading characteristic or essential feature or features.

In said drawing a, is the body; b, the border, and a and b, the carpet. 20

What I claim as my invention, and desire to secure by Letters Patent, is—

1. In a design for a carpet, the body a, substantially as shown.

2. In a design for a carpet, the border b, 25 substantially as shown.

3. The design for a carpet, consisting of the body a, and border b, substantially as shown.

In testimony whereof I have hereunto signed my name in the presence of two wit- 30 nesses.

ARCHIBALD F. REDDIE.
